MEANS FOR SNUBBING SPRINGS

Stacy B. Haseltine, La Grange, Ill., assignor to
 W. H. Miner, Inc., Chicago, Ill., a corporation
 of Delaware

Application May 3, 1943, Serial No. 485,427

2 Claims. (Cl. 105—197)

This invention relates to improvements in means for snubbing the action of railway car truck springs.

One object of the invention is to provide in a railway car truck simple and efficient means for snubbing or dampening the action of the usual truck springs of railway cars, thereby reducing the oscillations and vibrations of the springs to such an extent that the car and its lading will not be damaged.

Another object of the invention is to provide friction means of the character indicated in the preceding paragraph, auxiliary to the usual truck springs for dampening the recoil action of the springs to minimize the vibrations imparted to the car body.

Still another object of the invention is to provide a snubbing means comprising relatively movable cooperating friction elements at opposite sides of the usual spring cluster of the truck of a railway car, whereby the usual spring cluster without modification or substitution of other parts for any of the coils of the cluster may be employed on the truck.

A more specific object of the invention is to provide means as specified in the preceding paragraph, wherein the friction elements include a spring plank member having upturned side flanges, and a resilient plate forming the upper spring follower of the spring cluster, having depending sections in sliding frictional engagement with the upstanding flanges of the spring plank member.

Other objects of the invention will more clearly appear from the description and claims herein-after following.

In the drawing forming a part of this specification, Figure 1 is a top plan view of a portion of a railway car truck illustrating my improvements in connection therewith. Figure 2 is a side elevational view of the portion of the truck shown in Figure 1, looking in upward direction in said figure. Figure 3 is a horizontal sectional view, corresponding substantially to the line 3—3 of Figure 2. Figure 4 is a horizontal sectional view on the line 4—4 of Figure 2 of the right hand portion of the truck structure shown in Figure 2. Figure 5 is a top plan view of the upper follower for the spring cluster of the truck. Figure 6 is an edge elevational view of Figure 5, looking upwardly in said last named figure.

In said drawing, 10 indicates one of the side frame members of a railway car truck. The side frame 10, as shown, is in the form of a casting and has top and bottom members 11 and 12 con-

nected by spaced vertical sections 13—13 forming guides for the truck bolster. As will be understood by those skilled in this art, the truck includes two side frame members 10—10, and a truck bolster 14, a spring plank 15, and truck springs 16—16. The opposite ends of the spring plank are supported on the bottom members 12—12 of the side frames 10—10, and the opposite ends of the bolster 14 are guided between the sections 13—13 and 13—13 of the truck side frames. As most clearly shown in Figure 2, the sections 13—13 are inwardly offset at their upper end portions to provide guides 17—17 which co-operate with guide seats 18—18 at the sides of the bolster 14. The guides 17—17 are provided with the usual wear plates 19—19.

My improvements comprise broadly a friction element A in the form of a spring follower plate interposed between the bolster and the truck springs of the car, and a friction element B in the form of a spring plank, hereinbefore described and indicated by the character 15, the plate A having depending sections at opposite sides of the truck springs in sliding frictional engagement with the usual upstanding flanges of the spring plank.

The friction element A is in the form of a relatively wide plate formed of spring steel and having depending sections 20—20 at opposite ends, said depending sections being formed by bending the end portions of the plate at right angles to the main body thereof. The lower ends of the sections 20—20 are bent slightly inwardly, as shown, providing inclined sections 21—21. The horizontal main body portion of the plate A is provided with four downwardly projecting hollow bosses 22—22 adapted to engage within the coils of the spring cluster to center the individual springs thereof.

The friction member B is in the form of the usual spring plank having upstanding side flanges 23—23. The flanges 23—23 are relatively thick and have their inside surfaces inclined downwardly toward each other.

As shown most clearly in Figures 1 and 2 each spring cluster of the truck is composed of four springs. These spring clusters support the bolster 14 in the usual manner. The spring plank or friction member B rests on the bottom members 12—12 of the truck side frames 10—10 and supports the spring clusters, a spring follower plate 24 being preferably interposed between the bottom end of each cluster and the spring plank. The spring follower 24 is provided with the usual upstanding centering bosses 25—25 engaging

within the ends of the coils of the springs. The friction element A, which forms the upper spring follower for each cluster of truck springs, is interposed between the bolster 14 and the springs and has the inwardly bent ends 21-21 of the depending sections thereof in sliding frictional contact with the inclined inner surfaces of the flanges 23-23 of the spring plank 18.

In the operation of my improved spring dampening means, vibrations of the truck springs will be damped by sliding rubbing action of the sections 20-20 of the friction member A on the inner surfaces of the flanges 23-23 of the spring plank as springs 16-16 are compressed and expand during operation of the car, the friction elements A and B being moved relatively toward and away from each other corresponding to the relative movements of the bolster and truck side frames.

Inasmuch as the plate A is made of spring steel, its resiliency will hold the flanges 20-20 thereof in tight frictional engagement with the flanges of the spring plank, thereby producing sufficient frictional resistance to produce the desired dampening action. This frictional resistance increases slightly as the truck springs are compressed, due to the downward convergence of the friction surfaces of the flanges of the spring plank.

I have herein shown and described what I now consider the preferred manner of carrying out my invention, but the same is merely illustrative and I contemplate all changes and modifications that come within the scope of the claims appended hereto.

I claim:

1. In a truck spring snubber for railway cars having a truck provided with a spring support and a relatively movable truck bolster, the combination with a channel shaped spring plank member extending from side to side of said truck, said member having opposed, upstanding side flanges provided with opposed friction surfaces on the inner sides thereof, said friction surfaces converging downwardly; of a group of truck springs supported on said channel member at each end thereof; and a spring follower element interposed between each group of truck springs and the truck bolster of the car, each of said 10 spring follower elements comprising a plate of spring metal having depending flanges in sliding frictional engagement with the friction surfaces of said channel shaped spring plank member.

2. In a truck spring snubber for railway cars having a truck provided with a spring support and a relatively movable truck bolster, the combination with a spring plank carried on said spring support, said spring plank extending from side to side of said truck, said spring plank having rigid, upstanding side flanges having friction surfaces on the inner sides thereof; of a cluster of truck springs supported on said spring plank at each side of the truck; and a spring follower element at each side of the truck interposed between said springs and the truck bolster of the car, each spring follower element comprising a resilient plate having depending arms in sliding frictional engagement with the friction surfaces of said spring plank.

STACY B. HASELTINE.
